UNITED STATES PATENT OFFICE.

SPURGEON C. SCANTLEBURY, OF SPOKANE, WASHINGTON.

TOOL.

1,096,319.

Specification of Letters Patent. Patented May 12, 1914.

Application filed December 17, 1913. Serial No. 807,186.

To all whom it may concern:

Be it known that I, SPURGEON C. SCANTLEBURY, a citizen of the United States, residing in Spokane, in the county of Spokane and State of Washington, have invented new and useful Improvements in Tools, of which the following is a specification.

The object of this invention is to provide a tool for expanding a spring over the head 10 of a screw stud of eye-glasses so as to avoid the necessity of unriveting and removing the screw stud in order to position a spring thereon.

The device of my invention includes a 15 spring expander with means coöperating therewith to effect sufficient expansion of the spring to position the same upon the shank of the screw stud beyond the head thereof.

In the most improved embodiment of my 20 invention, I employ means of a resilient nature for clasping the spring expander in a manner to engage the spring so as to prevent rupture thereof when the spring is being expanded so as to be slipped over the 25 head of the screw stud.

Other objects and features of the invention will be more fully described in connection with the accompanying drawing, and will be more particularly pointed out and 30 ascertained in and by the appended claims.

In the drawing: Figure 1 is a view in elevation, illustrative of one form of my invention, showing the operation of expanding a spring with the glasses omitted. Fig. 2 is 35 a view in elevation, showing the manner of applying a spring to the screw stud of a pair of eye-glasses. Fig. 3 is an inner face view of one of the jaws of a pair of pliers. Fig. 4 is a sectional view thereof on line 40 4—4 of Fig. 3. Fig. 5 is a sectional view on line 5—5 of Fig. 3. Fig. 6 is a sectional view through parts of eye-glasses, which are united by a screw stud, the view being drawn on an enlarged scale.

45 Like characters of reference designate similar parts throughout the different figures of the drawing.

As illustrated, 1 designates a holder which may be in the form of a jaw of a pair of 50 pliers. A supporting base is indicated at 2, which may take the form of a companion jaw of the pliers.

When the invention is in the form of a 55 pair of pliers, the jaws are pivotally connected at 3 and are provided with handles

4 and 5, whereby the jaws may be manually operated.

The holder jaw 1 is provided with a holder portion in the form of a guiding aperture 6, and the supporting jaw 2 may be provided 60 with a supporting stud 7, which may be hollowed out for more effective engagement with the convex riveted end of the screw stud 8. I employ a coiled spring expander, which I have shown in the form of a tapered 65 mandrel 9, which is proportioned for passage in and through the guiding portion or aperture 6 of the holder or jaw 1.

In the most preferred embodiment of my invention, I employ a grasper for tightly 70 embracing the mandrel and engaging the spring to advance the same toward the larger end thereof, and I have provided an improved grasper adapted to snugly embrace the mandrel when advanced along its enlarging cross section so as to prevent the delicate coils of the spring from becoming wedged between and disrupted by engagement between the mandrel and the wall of 75 the guiding aperture 6.

80 My improved grasper, as shown, consists of a flat strip of resilient metal, as indicated at 10. The grasper strip is provided with an aperture 11, which is adapted to register, axially, with the guiding aperture 6 and 85 which is normally of considerably reduced diameter with respect thereto. The diameter of the opening 11 is preferably equal to, but may be slightly reduced with respect to, the diameter of the smaller end of the mandrel so as to just permit of starting insertion of the mandrel therethrough. I split the grasper strip 10 longitudinally thereof, as indicated at 12, and in order to increase its 90 spring action, I may reduce the strip 10 at 95 its split juncture, as indicated at 13, for a portion of the length thereof. In order to retain the mandrel grasper on the holder or jaw 1, I provide the latter with a screw stud 14, which may be of polygonal cross section 100 at 15, where it passes through an opening 16 in the grasper. The stud 14 is provided with a head 17 engaging the lower face of the grasper to hold the same in position. The polygonal portion of the stud 14 will 105 serve to maintain the opening 11 against displacement, laterally, from registry with the opening 6.

When the device of my invention is employed in connection with pliers of a type 110

wherein the jaws are not parallel, I prefer to elongate the opening 16 so as to provide for longitudinal movement of the grasper strip along the holder jaw 1 to accommodate for 5 differential movement during closure of diverging jaws. I also preferably bow the grasper strip, as clearly indicated at 18 in Fig. 4, so as to retain the apertured end in firm engagement with the apertured end of the holder jaw 1.

10 My invention also includes a mandrel catcher which is shown in the form of a tube 19 held in position to register with opening 6, so that when the spring has been 15 expanded and the mandrel has been released, the mandrel will be held between the resultantly contracted split ends of the strip 10 inside of the catching device 19. I have herein shown the catching device 19 mounted upon a support 20, which is shown pivoted at 21 to the jaw 1.

20 In Fig. 6 I have shown an enlarged sectional view through the parts united by the screw stud and the reduced shank of the latter is indicated at 22. The threaded end 25 is riveted or upset over the bridge shank 23 and interposed between the shoulder 24 and the bridge shank 23 is the collet 25 and the swinging guard 26. The head of the 30 screw stud is indicated at 27 and the coiled spring 28 is expanded over the head 27 onto the enlarged shank portion 29 so that the coils 28 will be interposed between the collet 25 and the head 27.

35 Describing the device of my invention when embodied in a pair of hand pliers, the spring 28 will first be disposed over the smaller end of the mandrel 9 and slightly advanced thereon to the position shown in 40 Fig. 1. The mandrel 9, or rather the smaller end thereof, will then be inserted through the opening 11 into a position to bring the upper convolution or wind of the spring into engagement with the grasper. 45 The grasper will be slightly expanded by insertion of the mandrel therethrough, so that the split portions of the grasper will snugly fit about the peripheries of the mandrel and engage the spring so as to advance the same 50 and positively prevent the upper wind of the spring from being crowded between the mandrel and the grasper. In some cases, I may oval the opening 11 in order to obtain a maximum accuracy of fit throughout engagement of the grasper with the gradually increasing cross section of the mandrel. The pliers are then opened to permit of the convexly rounded riveted end 8 being seated in the preferably concaved upper face of the 55 base cap 7, the head 27 being disposed beneath the larger end of the mandrel 9, and the latter being preferably concaved to facilitate maintenance of engagement in the disposition shown in Fig. 2. The jaws are 60 then gradually closed from the position 65

shown in Fig. 1 to the position shown in Fig. 2 and the spring 28 is expanded as it is advanced along the increasing cross section of the mandrel. The larger end of the mandrel is so proportioned with respect to the 70 head 27 that the spring will be forced over the head 27 when the jaws reach a final closing position. The concavity in the larger end of the mandrel is preferably of a greater radius than that of the head 27, so that a 75 final impulse in a closing direction on the handles 4 and 5 will serve to force the larger end of the mandrel up through the now extended split end of the strip 10 and contraction of the latter will snap the mandrel into the catching device into which the mandrel has been gradually projected during closing movement of the jaws. Thus the mandrel will be supported upon the abutting split ends of the strip 10, so as to be supported thereby in the catching device and be 80 retained therein until again used. When it is desired to again use the mandrel and tool, the former may be released from the catching device 19 by simply swinging the same 85 backwardly on the pivot 21.

In Fig. 6 I have shown an enlarged sectional view through the parts united by the screw stud and the reduced shank of the latter is indicated at 22. The threaded end 25 is riveted or upset over the bridge shank 23 and interposed between the shoulder 24 and the bridge shank 23 is the collet 25 and the swinging guard 26. The head of the screw stud is indicated at 27 and the coiled spring 28 is expanded over the head 27 onto the enlarged shank portion 29 so that the coils 28 will be interposed between the collet 25 and the head 27.

Expansion of the spring over the enlarged end of the mandrel will reduce the number of winds and enlarge the spring so that it will fit loosely about the screw stud. By grasping the opposite end of the spring and contracting the same, the number of winds will be increased to normal and the spring will be ready for location of its free ends in operative relation with the parts to be actuated thereby.

Heretofore it has been necessary to file off the riveted end of the screw stud and remove the latter in order to apply a new spring, and as it is usually necessary to perform this operation while the customer is waiting, and as it is not only a trying but difficult piece of work to do, it has heretofore been greatly dreaded even by the most skilful operators. By employing the device of my invention, this fussy and inconvenient detail of work is greatly facilitated and the risk of rupturing the delicate structure of the glasses frame is entirely avoided.

It is believed that the advantages and utility of my invention will be clearly understood from the foregoing description, and while I have herein shown and described one specific embodiment of my invention, I do not wish to be limited thereto except for such limitation as the claims may import.

I claim:—

1. As a means for expanding a coil spring over the head of an eye-glass stud screw, means for supporting the stud screw, a tapered mandrel for expanding the spring and adapted for engagement of its larger end upon said head, an apertured holder for retaining said mandrel in position and

- adapted to be advanced therealong toward said head, and expansible means interposed between the spring and said holder for gripping the mandrel throughout its movement therealong, substantially as described.
2. As a means for expanding a coil spring over the head of an eye-glass stud screw, a tapered mandrel for expanding the spring and adapted for engagement of its larger end with said head, expansible means gripping said mandrel and engaging said spring to advance the same along said mandrel and over said head, a holder for advancing said means onto said head to finally raise the mandrel out of grip and permit contraction of said expansible means to flip the mandrel away therefrom, and means for catching the mandrel, substantially as described.
3. As a means for expanding a coil spring over the head of an eye-glass stud screw, pliers provided with jaws and one thereof being adapted for engagement with the end of said screw, the remaining jaw being apertured, a tapered mandrel for expanding the spring and adapted to be partially inserted in the aperture of said jaw to hold its larger end upon the head of said screw, and an expansible means carried by said apertured jaw for gripping the mandrel and advancing the spring therealong upon contraction or closing movement of said jaws, substantially as described.
4. As a means for expanding a coil spring over the head of an eye-glass stud screw, pliers having one jaw adapted for supporting engagement with one end of said screw, the remaining jaw having a guiding aperture, a tapered mandrel for expanding the spring adapted to be projected into the aperture of said jaw with its larger end resting on said head, and a split spring plate carried by said apertured jaw and having an opening for grasping the mandrel to advance the spring therealong upon closing movement of said jaws, substantially as described.
5. As a means for expanding a coil spring over the head of an eye-glass stud screw, pliers having one jaw adapted for supporting engagement with the end of said screw, a tapered mandrel for expanding the spring, the remaining jaw being provided with a guiding portion for engagement with the mandrel and with the spring to advance the latter along the former and over the head of said screw, and a tubular mandrel catching device pivotally mounted on said apertured jaw for receiving the mandrel, substantially as described.
6. As a means for expanding a coil spring over the head of an eye-glass stud screw, pliers having one jaw adapted for supporting engagement with one end of said screw, the remaining jaw having a guiding aperture, a tapered mandrel for expanding the spring adapted to be projected into the aperture of said jaw with its larger end resting on said head, and a split spring plate slidably carried by said apertured jaw and having an opening for grasping the mandrel to advance the spring therealong upon closing movement of said jaws, substantially as described.
7. In a device for expanding a coil spring over the head of an eye-glass stud screw, a tapering spring expanding mandrel for the spring, mechanism comprising a base portion for supporting the screw stud at one end and a holder movable along the mandrel and engaging the larger end of the mandrel with the head end of the stud screw to firmly hold the same and advance the spring along the mandrel over the larger end of the latter and over the head of the stud screw, and means interposed between the spring and the holder for preventing rupture of the former by the latter, substantially as described.
8. In a device for expanding a coil spring over the head of an eye-glass stud screw, a tapering spring expanding mandrel for holding the spring, a base portion for supporting the screw stud at one end, a holder movable along the mandrel and engaging the larger end of the mandrel with the head end of the stud screw to firmly hold the same and advance the spring along the mandrel over the larger end of the latter and over the head of the stud screw, and means carried by the holder and disposed between the latter and the spring for gripping the mandrel to prevent rupture of the spring coils by the holder, substantially as described.
9. In a device for expanding a coil spring over the head of an eye-glass stud screw, mechanism including a tapering spring expanding mandrel for holding the stud screw firmly in position and advancing the spring along the mandrel over the head of the stud screw, and means interposed between the spring and a portion of said mechanism for preventing rupture of the spring, substantially as described.
10. In a device for expanding a coil spring over the head of an eye-glass stud screw, mechanism including a spring expander for holding the stud screw firmly in position and advancing the spring along the mandrel and over the head of the stud screw, and spring means gripping the expander and actuated by said mechanism for direct engagement with the spring to prevent rupture of the latter by said mechanism, substantially as described.
11. As a means for expanding a coil spring over the head of an eye-glass stud screw, pliers provided with jaws and one thereof being adapted for engagement with the end

of said screw, the remaining jaw being apertured, a tapering mandrel for expanding the spring and adapted to be partially inserted in the aperture of said jaw to hold 5 its larger end upon the head of said screw, a split leaf spring adjustably carried by said apertured jaw and being bowed between its ends away from said apertured jaw and having an aperture in its split 10 portion for movement along the mandrel

and between said spring and said apertured jaw, substantially as described.

In testimony that I claim the foregoing as my own, I hereby affix my signature in the presence of two subscribing witnesses.
